UNITED STATES PATENT OFFICE.

WESLEY P. HARPER, OF LATROBE, PENNSYLVANIA.

HORSE-DETACHER.

SPECIFICATION forming part of Letters Patent No. 618,665, dated January 31, 1899.

Application filed June 6, 1898. Serial No. 682,665. (No model.)

To all whom it may concern:

Be it known that I, WESLEY P. HARPER, a citizen of the United States of America, residing at Latrobe, in the county of Westmoreland and State of Pennsylvania, have invented certain new and useful Improvements in Horse-Detachers, of which the following is a specification, reference being had therein to the accompanying drawings.

10 My invention relates to certain new and useful improvements in horse-detaching devices.

15 The object of my invention is to provide a device of this character whereby the horse can be automatically released from the shafts and singletree.

20 My invention consists in pivotally securing to the ends of the singletree a spring-actuated device, hereinafter more fully described, for securing the trace and removing the same therefrom and a removable securing means secured to the shafts for the back-strap.

25 My invention further consists in the novel combination and arrangement of parts hereinafter more fully described, illustrated in the accompanying drawings, and particularly pointed out in the claims hereunto appended.

30 In the drawings, Figure 1 is a perspective view of a part of my improved detaching and securing means for the trace attached to one end of the singletree. Fig. 2 is a side view of the detaching device for the trace, showing in dotted lines the position thereof when the trace is released from the singletree. Fig.

35 3 is a side view of the detaching and securing device for the back-strap, showing in dotted lines the back-strap when released, with rod attached thereto. Fig. 4 is a perspective view of the detaching and securing means for the back-strap with the part detached. Fig. 5 is a perspective view of the detaching and securing means for the trace.

40 Like numerals of reference indicate corresponding parts throughout the several views of the drawings, in which—

45 1 indicates the shaft, having the singletree 2 attached thereto in the usual manner; 3, the trace, and 4 the back-strap. The singletree 2 has the tapering extensions 5 secured

50 to each end thereof to receive the ends of the trace. Pivots secured, as at 6, to the extension 5 is the trace keeper or securer,

which is formed of a vertical bar 7, extending above and abutting against the free end of the extension 5, and has formed integral therewith a horizontal bar 8, which converges outward from its center and is bent at a right angle, as at 9. The bar 8 is adapted to fit over the extension 5, owing to the interior of the end of the same, or rather the converging portion of the bar, being cut away, as at 10, thereby forming an opening in the bar.

Pivoted in the free end of the bar 8 is a horizontal bar 11, a part of which is bent 65 downwardly, as at 12, and fits over the extension 5, owing to an opening being cut in the end of the bar, as at 13, and is adapted to detach the trace from the extension 5. Secured to the ends of the bars where they are 70 pivoted together, as at 14, is a spring 15. The opposite end of the spring 15 is secured to the upper edge of the singletree, as at 16. This spring 15 is adapted to hold the bars in position until released by the pulling of the 75 strap 17, the end of which is secured to the ring 18, formed integral with the lower end of the bar 7. The opposite end of the strap 17 is connected to a ring 19 near the center of the singletree and on its under side, and the ring 19 has also connected thereto the straps 20 and 20'.

Secured to the under side of the shaft 1 is an oblong plate 21, having an elongated groove 21' formed therein to receive a bar 85 22, the free end of which is enlarged, as at 23, and has an opening 24 formed therein to have secured thereto the back-strap 4.

When it is desired to release the horse, the strap 20' is pulled toward the person 90 holding the same, thereby causing the straps 17 and 20 to move and from their movement pull the bars 7 and 8 downwardly, forcing the bar 11 outwardly, and the ends of the same force the trace from the extension 5. The 95 horse is then free, lacking the connection of the back-strap, which, as the horse moves forward, the bar 22 to which the back-strap is connected is pulled outwardly from the groove 21' in the plate, and the horse is then 100 entirely free.

Having thus described my invention, what I claim, and desire to secure by Letters Patent, is—

1. In a horse-detacher, a singletree, a retaining means for the trace, said retaining means consisting of a horizontal bar extending underneath the end of the singletree, 5 arms 9, formed integral therewith and extending at right angles to the bar, said arms being pivoted centrally of their length to the singletree and connected at their upper ends, a releasing means for the trace, said releasing means consisting of a horizontal bar 11, pivotedly connected at its rear end to the upper end of the arms 9, and having formed integral with its forward end an open frame to receive the end of the singletree, and a 10 spring secured to the said singletree and to the upper ends of the arms 9, for holding the parts in their normal position and for returning same to such position after having been operated, substantially as shown and de- 15 scribed.

2. In a horse-detacher, the combination with a singletree of a retaining means for the trace consisting of a bar 8 having an extension 7 and arms 9 formed integral therewith, said arms 9, being pivotally connected 25 to the singletree, a retaining means consisting of a bar pivotally connected to the upper ends of the arms 9 and formed at its outer end with an open frame to receive the end of the singletree, a spring connected to said 30 arms 9 and to the singletree, and means for simultaneously operating the retaining and releasing means, substantially as shown and described.

In testimony whereof I affix my signature 35 in the presence of two witnesses.

WESLEY P. HARPER.
